UNITED STATES PATENT OFFICE.

PATRICK B. DELANY, OF SOUTH ORANGE, NEW JERSEY, AND NANTUCKET, MASSACHUSETTS, ASSIGNOR TO TELEPOST COMPANY, OF NEW YORK, N. Y., A CORPORATION OF MAINE.

AUTOMATIC TELEGRAPHY.

1,141,868.

Specification of Letters Patent.

Patented June 1, 1915.

Original application filed December 29, 1903, Serial No. 469,804. Divided and this application filed April 27, 1911. Serial No. 623,603.

To all whom it may concern:

Be it known that I, PATRICK B. DELANY, a citizen of the United States, residing at South Orange, county of Essex, State of New Jersey, and at Nantucket, county of Nantucket, State of Massachusetts, have invented a certain new and useful Improvement in Automatic Telegraphy, of which the following is a specification.

This invention relates to automatic receivers and provides a means by which is insured proper contacts of the transmitting devices operating through perforations in the ordinary transmitting tape. It has been found that revolving drums over which the tape passes accumulate dirt on their surfaces which makes contacting unreliable. Stationary contacts of opposing brushes are effective but somewhat troublesome to adjust. I have found that a stationary contact presenting a sharp edge to an elastic contact finger pressing against it gives never failing connection. Dirt cannot accumulate on the edge to any appreciable degree and should it do so the pressure of the elastic contact is more than sufficient to cut through it. Any of the forms shown will afford perfect contact at any speed. Below the tape there is located a non-elastic part having an edge against which the upper elastic transmitting contact finger comes into contact through perforations in the tape. The preferred form of the device is that of a toothed wheel against the edges or ends of the teeth of which the transmitting contact finger comes into contact when a perforation passes between the two. This wheel although normally stationary is capable of rotation so that from time to time a new tooth thereof may be brought into position to be engaged by the contact finger. When both of the transmitting contact fingers are on top of the tape, as in the well known Delany system, their relative adjustment is sometimes troublesome. By using a toothed circuit wheel to coöperate with each finger the adjustment and behavior of the apparatus is much simplified.

In the accompanying drawing: Figure 1 is a detail diagrammatic view showing two transmitting circuit wheels having teeth coöperating with yielding contact fingers bearing upon the upper surface of the tape

which passes over the wheels. Fig. 2, a similar view showing a modification; and Fig. 3 shows transmitting contact blades against the edges of which bear the upper contact fingers when perforations in a tape pass between them.

The contact wheels M in Fig. 1 are of course insulated from each other and are fixed to turn together about a common axis. They have ordinary ratchet teeth *m* with which coöperate the line transmitting fingers *f*. *L* indicates the line. The paper tape passes between the teeth of the wheels and the transmitting fingers *f*. The wheels are adapted to be rotated step by step to bring, from time to time, into operative relation to the transmitting fingers different teeth of the wheels. The traverse of the tape serves to keep clean and well burnished the contact faces or edges both of the wheel teeth and the transmitting fingers.

In Fig. 2, the wheels are marked M'. They are not like ordinary ratchet wheels but have thin radial blade-like teeth marked *m'*.

In Fig. 3, instead of the toothed circuit wheels there are two fixed relatively rigid blades *q*, *q'* with the edges of which the flexible transmitting fingers *f* contact through the perforations of the tape. The fingers *f* are preferably each composed of a plurality of wires.

This application is a division of my application, No. 469,804, filed December 29, 1903.

I claim:

1. In an automatic telegraph transmitter a circular contact member having a plurality of contact edges against which bears, through perforations of a transmitting tape, a fixed signal transmitting contact.

2. In an automatic telegraph transmitter a contact wheel having a plurality of contact edges and a coöperating fixed transmitting contact finger, said wheel being adapted to be set to hold in position any one of the edges to be acted upon by the contact finger, combined with means for making and breaking contact of the active edge and finger.

3. In an automatic telegraph transmitter, a rotatable contact wheel having a plurality of contact edges combined with a fixed transmitting contact coöperating with said

edges, an electric circuit including the wheel and transmitting contact and means for actuating the contact to break the circuit.

4. In an automatic telegraph transmitter, a normally fixed contact wheel adapted to be rotated and having a plurality of contact edges combined with a fixed coöperating transmitter contact and means for actuating the contact to break the electric circuit in which the wheel and contact are included.
5. In an automatic telegraph transmitter,

a fixed flexible contact maker combined with a series of interchangeable contact makers each having an edge against which the flexible contact maker is adapted to press through perforations in a transmitting tape.

In testimony whereof, I have hereunto subscribed my name.

PATRICK B. DELANY.
